MOUNTING FOR POWER TOOL

Theron L. Hedgpeth, Oak Park, Ill., assignor to
Duro Metal Products Company, Chicago, Ill.,
a corporation of Illinois

Application May 10, 1939, Serial No. 272,815

5 Claims. (Cl. 248—124)

This invention relates to a mounting for power tools and has for its principal object to provide an improved mounting whereby power hand tools may be readily mounted in various positions and for various purposes so as to convert them, in effect, into machine tools. The invention will be particularly described in connection with the power hand tool described and claimed in my co-pending application Serial No. 258,667 filed February 27, 1939. It will, however, be readily understood that the invention is applicable generally to other power hand tools of the same general type.

The invention will readily be understood from the following description of a preferred embodiment thereof, taken in conjunction with the accompanying drawings, in which:

Figure 1 is a sectional elevation of a mounting for a power hand tool, whereby the same may be adapted for use as a shaper;

Fig. 2 is an elevational view of the upper part thereof;

Fig. 3 is a sectional plan view, the section being taken on the line 3—3 of Fig. 1.

Fig. 4 is a plan view of the shaper table;

Fig. 5 is a plan view showing the mounting arranged to adapt the hand tool for use as a power grinder;

Fig. 6 is an elevation as viewed from the upper side of Fig. 5, and

Fig. 7 is a further elevation as viewed from the right in Fig. 5.

Referring to the drawings, the hand tool referred to comprises a housing 10 of generally pear-shape outline, as indicated in dash-and-dot lines in Figs. 1, 2 and 5. The principal portion of the housing 10 is, as shown in Fig. 3, substantially cylindrical in form, but is provided with two opposed generally flat sides 11. These flat sides are provided with longitudinal flutings or corrugations, as best seen in Figs. 3 and 7.

The tool comprises a switch 12, a cable 13 whereby its motor may be energized, and a chuck 14 which rotates with the rotor of the motor and which is adapted to receive the spindles of cutting tools, bores or abrasive elements indicated generally by the reference numeral 15.

My improved mounting comprises a pedestal 16 which may, as best shown in Fig. 1, be a hollow casting which has a large base portion 17 adapted to rest on a bench. At a position near its center the casting is provided with a boss 18 for the reception of a wood screw 19 whereby the pedestal may be firmly secured to the bench. The

pedestal 16 extends upwardly in general conical form, the upper portion being a solid head 20.

The head 20 of the pedestal is provided with a transverse bore 21 which receives a pivot pin 22. This pivot pin is held stationary within the bore 21 by means of a set screw 23. The head 20 is also provided with a transverse slot 24, the plane of which lies at right angles to the direction of the pivot pin 22.

As best seen in Fig. 1, the pivot pin 22 extends across the slot 24. The slot 24 receives one length of an angle member 25, this length having an opening 26 through which the pivot pin 22 passes. It will readily be understood that the pin 22 serves as a pivot for the angle member 25 so that the other outer length of the angle member 25, which is indicated by the reference numeral 27, may be located at various positions with respect to the pedestal 16 while still maintaining its general horizontal position.

The angle member 25 may be secured in any desired position of adjustment by means of the thumb screw 28. Upon the length 27 of the angle member 25 is rigidly mounted a bolt 29 which is directed outwardly away from the pivot pin 22 and is located at right angles to the axis of the pivot pin. The bolt 29 is parallel to the axis of the length of the angle member 25 which is received in the slot 24.

My improved tool mounting also includes a mounting ring designated generally by the reference number 30. This mounting ring comprises a major annular portion 31 which is adapted to receive the body of the tool, as shown in the drawings. On one side the annular portion 31 has mounted within it a bearing plate 32. This bearing plate provides a central recessed portion 33 and upper and lower portions 34 which are of corrugated form and are adapted to engage the flat sides 11 of the tool, which flat sides are provided with similar longitudinal flutings or corrugations, as best seen in Figs. 3 and 7.

The vertical margins of the bearing plate 32 are provided with exterior formations 35 corresponding to the curvature of the annular portion 31. The plate 32 is secured in position by means of the screw 36 which draws the plate 32 outwardly with its formations 35 firmly abutting against the inner side of the annular member 31.

On the opposite side of the annular member 31 is provided a movable abutment plate 37 which is substantially similar to the plate 32, with the exception that it is rigidly mounted on a screw 38 and that it is capable of moving in the radial direction of the annular member 31.

The screw 38 is a left-hand screw which projects through an opening 39 in the annular member 31 and through an opening 40 in the loop member 41, which is integral with the annular member 31. Within the loop 41 the screw 38 carries a nut 42 having a milled or knurled periphery. On the outer side of the nut 42 is located a washer 43 which is adapted to abut against the nut 42 and against the outer side of the loop 41. The nut 42 is provided with a series of radial openings 44 adapted to receive a capstan bar for applying leverage to the nut for securing the tool 10 firmly in its mounting.

It may be noted that on the outer side of the abutment plate 37 the annular member 31 is recessed slightly to permit the abutment plate 37 to be moved clear of the tool 10, as indicated at 45.

To mount the tool 10 in the annular member 31, the nut 42 is rotated in the left-hand direction so as to draw the plate 37 into the recess 45. The tool is then placed in position with the corrugated sides 11 opposite the abutment plates 32 and 37. The nut 42 is then rotated in the clockwise direction so as to project the plate 37 inwardly until it engages the adjacent side 11. It may here be noted that the plate 37 is prevented from rotating by its relation with the annular member 31. The projection of the abutment plate 37 forces the remote side 11 into engagement with the abutment plate 32.

The abutment plate being stationary, defines the exact direction of the axis of the tool. The plate 37 being capable of a limited rotation about the axis of the screw 38, locates itself owing to the engagement of its corrugations with the corrugations of the adjacent side 11 of the tool. The nut 42 is tightened by means of a capstan bar which is entered into certain of the openings 44 and when the tool is finally mounted in position, the nut 42 bears strongly against the washer 43 which bears against the outer side of the loop 41.

The annular member 31 is provided on one side with a lug 46 which is provided with an opening 47 having an axis parallel to the axis of the annular member 31. The opening 47 is adapted to receive the bolt 29 and the mounting ring 30 may be rigidly secured to the angle member 25 by means of a nut 48 and washer 49.

It will thus be seen that the tool 10 has, in effect, a universal mounting upon the head 20 of the pedestal. Owing to the pivotal mounting of the tool upon the pedestal about the axes of the pivot 22 and the bolt 29, the tool may be directed in practically any desired direction. Thus, as shown in Figs. 1, 2 and 3, the tool is directed upwardly. By simply loosening the thumb screw 28 and swinging the tool about the pivot pin 22, the tool 10 may be moved into the horizontal position shown in Figs. 5, 6, and 7.

By adjusting the tool 10 around the bolt 29 as axis, the location of the tool 10 with relation to the pedestal 16 may be changed without changing its direction. This enables the tool 10, as shown in Fig. 1, to be swung around the pedestal to more convenient locations while still preserving its vertical direction. When the tool is in horizontal position, as shown in Figs. 5, 6 and 7, it may be swung around the bolt 29 in order to locate the tool at a certain height.

It will, of course, be understood that other accessories may be readily applied to the tool and to the mounting. Thus, in Fig. 1 I have shown a post 50 which has a threaded recess whereby it may be rigidly mounted on the upper or outer end

of the bolt 29. The post 50 is provided with a shoulder 51 and beyond this shoulder it comprises a round bar-like portion 52. The bar-like portion 52 is adapted to extend through a boss 53 on an attachment such as a shaper table 54.

The shaper table may be held stationary by means of a thumb screw 55 mounted in the boss 53 and adapted to engage the post 52. The shaper table 54 is provided with an opening 55' through which may extend the cutting tool or 10 bit 15 and the spindle which carries it. The shaper table 54 may be provided with adjustable guides 56 and 57 of desired type.

Although the invention has been disclosed in connection with the specific details of a preferred embodiment thereof, it must be understood that such details are not intended to be limitative of the invention except in so far as set forth in the accompanying claims.

Having thus described my invention, what I claim as new and desire to secure by Letters Patent of the United States is:

1. A mounting for a power tool comprising a pedestal having an upwardly projecting end portion, an angle member mounted on said end portion for movement about a horizontal axis, means on said angle member defining an axis at right angles to the first said axis and in displaced relation to said end portion, a mounting ring adapted to be secured to last said means in desired relation thereto, and means for securing said angle member in desired position of adjustment about the first said axis.

2. A mounting for a power tool comprising a pedestal having a vertical slot in its upper end, a horizontal pivot pin in said pedestal extending across said slot, an angle member having one length received in said slot, said length being provided with an opening through which the pivot pin extends, set screw means on said pedestal for holding said angle member rigidly thereon, a bolt rigidly mounted on the other length of said angle member in displaced relation to said upper end of the pedestal and at right angles to said other length, said bolt being at right angles to the pivot pin, a mounting ring for a power tool having a perforated lug whereby the ring may be mounted on said bolt in pivotal relation thereto, and means for securing said ring rigidly to said bolt.

3. A mounting for a power tool comprising a pedestal having a vertical slot in its upper end, a horizontal pivot pin in said pedestal extending across said slot, an angle member having one length received in said slot, said length being provided with an opening through which the pivot pin extends, set screw means on said pedestal for holding said angle member rigidly thereon, a bolt rigidly mounted on the other length of said angle member, said bolt being at right angles to the pivot pin, a mounting ring for a power tool having a perforated lug whereby the ring may be mounted on said bolt in pivotal relation thereto, means for securing said ring rigidly to said bolt, said mounting ring having a stationary abutment plate on its interior and a movable abutment plate in opposed relation, a threaded member projecting radially through the ring and carrying said movable plate, a loop member integral with said ring and located on the exterior side thereof, said threaded member extending through said loop member, and nut means on said threaded member and within said loop member adapted to effect the inward movement of the

movable abutment plate to clamp the tool in the ring.

4. In a mounting for a power tool, a mounting ring having a perforated lug on its exterior, a stationary abutment plate on its interior and a movable abutment plate in opposed relation, a threaded member rigidly mounted on said movable plate and projecting outwardly through the ring, a loop member integral with the ring and on the exterior side thereof, said threaded member extending through the loop member, and a nut member mounted on said threaded member, located within the loop member and adapted to effect the inward and outward movement of the movable abutment plate.

5. In a mounting for a power tool, a mounting ring having a perforated lug on its exterior, a stationary abutment plate on its interior and a movable abutment plate in opposed relation, a bolt having a left-hand thread rigidly mounted on said movable plate and projecting outwardly through the ring, a loop member integral with the ring and on the exterior side thereof, said bolt extending through the loop member, and a nut member mounted on said bolt, located within the loop member and adapted to effect the inward and outward movement of the movable abutment plate. 5 10 15
